CLAIM

The ornamental design for a “snowshoe”, as shown and described.

DESCRIPTION

FIG. 1 is a perspective view of first embodiment of the “snowshoe design” of this invention also illustrating the front side and right side views; the left side view not illustrated but being identical and symmetrical to the right side view;

FIG. 2 is a bottom plan view of FIG. 1;

FIG. 3 is rear side elevation view of FIG. 1;

FIG. 4 is a perspective view of a second embodiment of the “snowshoe design” of this invention also illustrating the front side and right side views; the left side view not illustrated but being identical and symmetrical to the right side view;

FIG. 5 is a bottom plan view of FIG. 4;

FIG. 6 is a rear side elevation view of FIG. 4;

FIG. 7 is a perspective view of a third embodiment of the “snowshoe design” of this invention, also illustrating the front side and right side views; the left side view not illustrated but being identical and symmetrical to the right side view;

FIG. 8 is a bottom plan view of FIG. 7; and,

FIG. 9 is a rear elevation view of FIG. 7.
